(57) **CLAIM**

The ornamental design for a collagen membrane, as shown and described.

DESCRIPTION

1. Collagen membrane

1.1 is an elevated perspective view of a collagen membrane;

1.2 is a top plan view thereof;

1.3 is a left side plan view thereof, the right side plan view being a mirror image of the left side plan view;

1.4 is a front plan view thereof; and

1.5 is a back plan view thereof.

1 Claim, 5 Drawing Sheets(56)
